WILLIAM P. BOVARD, OF MANSFIELD, OHIO, ASSIGNOR TO THE OHIO BRASS COMPANY,
OF MANSFIELD, OHIO, A CORPORATION OF NEW JERSEY.

VALVE.

1,281,496.

Specification of Letters Patent.

Patented Oct. 15, 1918.

Application filed May 31, 1917. Serial No. 171,828.

To all whom it may concern:

Be it known that I, WILLIAM P. BOVARD, a citizen of the United States, residing at Mansfield, in the county of Richland and 5 State of Ohio, have invented certain new and useful Improvements in Valves, of which the following is a specification.

My invention relates to that class of devices known as valves suitable for use on either water or steam lines and finds most 10 general use in connection with hot water and steam heating systems.

It has for its object a device which is simple and easy of construction; a device which 15 is proof against leakage around the valve stem; a device in which the packing is as far removed from contact with the steam or water as possible, thereby maintaining the packing at a more nearly constant temperature 20 or that of the surrounding air. Other objects and benefits of this device will be pointed out and disclosed as the invention is more fully described and explained as to construction and operation.

25 In the views or figures I show an angle type of valve but my invention is adapted to a straight-of-way type of valve equally as well.

It will be observed that those parts of the 30 valve which affect the joint packing around the stem to prevent leakage are so constructed and combined as to practically constitute a single working unit and the construction is such that the flow of steam, water or other fluid which the valve may be used with, is minimized or retarded from flowing into the chamber in which the spring is located, by a reasonably close fit between the valve stem and its guide. This 35 fact, together with the extreme location of the packing from the source of inlet of the fluid, places the packing under the most favorable conditions for constant working temperature and thereby relieving the packing of extreme high temperature or variation where the valve is used with steam.

As the construction of my valve is simple and the parts are practically symmetrical; that is, being of a circular cross section, I 50 have shown only one figure embodying my improvements which is a longitudinal sectional view with some of the interior parts in full, and this is shown in Figure 1. Fig. 2 is a cross sectional view on the line 2-2 of

Fig. 1. Fig. 3 is a perspective view of the 55 U-shaped washer which is essential in order to properly assemble the important working parts of my invention.

A description of my invention is as follows—Numeral 1 indicates the valve body 60 of the usual design and shape having an inlet and outlet opening, 2 and 3 respectively, which are provided with attaching means; 4 indicates a bonnet casting attached to the body 1 by a threaded and shouldered 65 joint to prevent leakage. The passage way from openings 2 and 3 through the valve body is closed or opened through the medium of the valve 5 which is provided with a composition disk 6, although other forms 70 of disks of other material may be used. The disk 6 is adapted to press against a raised portion 7 called the valve seat, for closing off the flow of fluid through the valve body. The valve disk is held in place through the 75 medium of the washer 8, the nut 9 and the threaded stem 10. The disk 6 is provided with a projection 11 which engages with a threaded extension 12 and the end of the projection 11 is peened over so as to prevent 80 the parts 5 and 12 from being disconnected but permits the two to revolve with respect to each other if desired, or the end of the stud 11 can be peened over so that there is no relative movement of the disk 6 with 85 respect to the threaded extension 12. The outside of the threaded extension 12 is provided with a very coarse thread 13 which engages with the corresponding coarse 90 thread 14 on the bonnet 4 so that as the 95 threaded extension 12 is revolved it is caused to rise or fall with respect to the bonnet and thereby causing the composition disk 6 to rise and fall, closing or opening the passage way through the valve. The upper end of the valve extension 12 is provided with an opening of such contour as to receive the valve stem 15 and the two are arranged to prevent relative rotation but to permit the two to slide longitudinally upon 100 each other as the valve stem 15 is fixed as to longitudinal movement while the threaded extension 12 is arranged for longitudinal movement coincident with its rotation.

The chamber 16 in the bonnet 4 serves to 105 allow space for the rise and fall of the threaded extension 12 and it also acts as a chamber for catching the leakage past the

threaded joint between the parts 12 and 4, thereby producing a water seal, and which has a lower temperature than that of the fluid passing through the valve when such 5 fluid is steam.

The upper end of the bonnet 4 is provided with a spring case cap 17 which is threadedly attached thereto. The recess 18 produced by the parts 4 and 17 contains the 10 spring 19 and the retaining U shaped washer 20 also shown in Fig. 3.

The stem 15 is provided with an annular groove 21 adapted to receive the U shaped washer 20 the washer being slidable sideways on the stem. Below the groove 21 is a 15 flange 22 which makes a reasonably close fit in an aperture 23; this arrangement not only acts as a guide for the stem 15 but the close fit of the part tends to reduce and materially 20 minimize the pressure and flow of fluid from the chamber 16 into the chamber 18. The upper face of the cap 17 is provided with a circular ridge 24 although several of these ridges placed concentrically may be used.

25 An outwardly projecting flange 25 forms an integral part of the stem 15 at its upper end and the lower face of this flange is provided with circular raised ridges 26 which may be one or more in number and concentric with 30 respect to each other. The flange 25 is provided with a downwardly extending flange 27, the purpose of which is largely one of appearance. In the cavity 28 thus formed is a composition packing disk 29 which is 35 seated between the packing ridges 24 and 26 and the three parts 24, 26 and 29 are firmly pressed into contact through the action of the spring 19. It will be observed and readily understood, that with sufficient spring 40 pressure, leakage from the inside of the valve to the outside will be entirely eliminated by the construction which I have shown and described, and that the packing 29 is removed from the main source 45 of temperature as far as it is possible to do so, and yet produce a compact valve. It will also be observed that the pressure of the fluid upon the packing disk and joint are materially reduced through the relation of the 50 parts 22 and 23 and the relation of the parts 12 and 4.

The upper face of the flange 25 is provided with two or more projections 30 which are seated in depression 31 in the handle 32 55 which is usually constructed of wood, and the handle 30 is held in place on the stem 15 by means of the screw 33. The simplicity of the assembly of the parts 15, 17, 19, 20 and 29, which might be stated to constitute 60 a single working unit for the reason that by unscrewing the cap 17 all of these parts are disassembled as one unit, will be appreciated when it is considered that all that is necessary is to place the disk 29 on 65 the stem 15, insert the stem 15 through the

cap 17, place the spring 19 in position and then to place the washer 20 in the groove 21, and these parts as a unit are then placed in position upon the bonnet 4 and when screwed tightly into place the valve is thoroughly and well protected against leakage. 70

The assembled valve as I propose to construct it, constitutes a device which by turning the handle 32, causes the valve 5 to rise or fall according to the direction the handle 75 is turned, thereby opening or closing the passage between the openings 2 and 3, and the spring 19 is constantly causing a tight fitting between the parts 24, 26 and 29, thereby constantly and automatically maintaining 80 a nonleakage condition between the interior of the valve and the exterior around the stem 15.

Other modifications may be made by those skilled in the art from the construction 85 which I have described and disclosed herein without departing from the spirit and scope of my invention, and therefore I do not care to be limited to the exact construction shown.

What I claim as new is:

90 1. A valve comprising in combination with a casing, a valve seat therein, a valve for the seat, a cap on the casing, a stem for operating the valve and having a flange thereon and packing means engaged by the cap and flange, of yielding means interior of the case for maintaining the cap, packing and flange in sealed relation and means slidable sideways on the stem to maintain and support the yielding means. 100

95 2. A valve comprising a casing, a valve seat formed therein, a valve for the seat, a stem, a cap, a flange on the stem but exterior of the cap, a packing member interposed between the cap and flange, means for 105 yieldingly and automatically retaining said packing member in frictional contact with the cap and flange, and a U-shape washer mounted on the stem for supporting one end of said yielding and automatic means. 110

115 3. In a valve, a casing, a cap removably secured thereto provided with an annular ridge formed on the exterior surface of the end thereof, a stem rotatably mounted, a flange on the stem having an annular ridge formed on the lower face thereof, and provided with a depending sleeve, a packing member interposed between the cap and flange, and surrounded by the sleeve, a spring, and a U shape washer removably 120 mounted on the stem adapted to provide a means for retaining the packing member, cap and spring in a predetermined relation with the flange.

125 4. In a valve, a casing having a guide formed therein, a stem mounted in the guide and in close relation thereto, a flange provided on the stem, a cap secured to the casing, a packing member interposed between said cap and flange, a spring, and a U 130

shape washer removably mounted in a groove on the stem adapted, when in position, to combine the stem, packing member, cap and spring into a single working unit, 5 substantially as described.

5. The combination with a valve body, valve seat and valve, of a cap, a stem having a non-rotatable but longitudinally sliding engagement with the valve and having 10 also a flange formed integral with the stem exterior of the cap, a packing disk between the cap and flange, a spring within the cap and means within the cap for retaining the cap, stem, packing and spring in an assembled state, permitting these parts to be taken 15 off and reapplied as a single unit.

6. The combination with a valve body, valve seat and valve, of a cap, a stem provided with an exterior flange passing 20 through the cap, a packing disk interposed between the cap and flange and a spring within the cap for yieldingly pressing the packing between the cap and flange, and means slidably mounted to move sidewise

on the stem to support and maintain the 25 spring.

7. The combination with a valve body, valve seat and valve, of a cap, a stem provided with an exterior flange, a packing disk 30 interposed between the cap and flange, a resilient member within the cap for pressing the packing between the cap and the flange, and means positioned interior of the valve for locking the cap and stem in yielding engagement with the packing. 35

8. An article of manufacture comprising in combination a recessed body member, an apertured cap positioned on the body member, a stem passing through the recess and apertured cap, a flange on the stem exterior of the body member, a packing member positioned between the flange and the cap, a resilient member and means engaging the stem within the recess for maintaining all parts together as a unit. 40 45

In testimony whereof I affix my signature.

WILLIAM P. BOVARD.
